UNITED STATES PATENT OFFICE.

JOHN M. COLLINGWOOD, OF WICHITA, KANSAS.

GOLF-BALL TEE MOLD.

Application filed July 9, 1923. Serial No. 650,417.

To all whom it may concern:

Be it known that I, JOHN M. COLLINGWOOD, a citizen of the United States, residing at Wichita, in the county of Sedgwick and 5 State of Kansas, have invented certain new and useful Improvements in a Golf-Ball Tee Mold, of which the following is a specification.

This invention relates to molds, particularly adapted for use by golf players, for forming tee molds for supporting a golf ball.

10 A further object of my invention is to provide a tee mold, whereby the mold which 15 is in the shape of a pyramid is provided with a recess for supporting a ball therein.

15 A further object of my invention is to provide a mold which can be forced downwardly into a box containing damp sand, 20 and whereby the sand mold will be automatically formed therein, and a spring plunger operated through the handle of said mold, whereby the sand mold is extracted from the mold and at the same time a recess 25 is made in the top of same for receiving a golf ball therein.

And a still further object of the invention 30 is to provide a tee mold, which is simple in construction, durable, efficient for the purpose intended, and one that can be manufactured and placed on the market at a relatively low cost.

These and like objects of the invention 35 will be better understood as the description follows and as is specifically pointed out in the appended claim.

Referring to the accompanying drawing 40 which forms a part of this specification and which clearly shows the construction and operation of my improved mold,

Figure 1 is a side elevation of a mold constructed in accordance with my invention.

Figure 2 is a top plan view of same, and

45 Figure 3 is a vertical section through same.

At the present time two practices are 50 used for forming tee molds, one of which is to dig the sand out of the sand box and form the mold by hand. This has proven satisfactory, except that it soils the hands and clothes of the golf player. The second method adopted has been to provide a mold of rubber. This has also proven satisfactory, except that in some instances the golf 55 player will strike the mold when swinging at the ball, which will cause the mold to roll

a considerable distance from the tee, which often results in same being lost. As this happens quite often, the latter method has been found to be too expensive for practical use.

My improved tee forming mold comprises a cone shaped cup 1 having a hollow cone shaped recess 2 therein and a handle 3 formed on the reduced end of the cup 1.

The handle 3 has a central bore 4 extending vertically therethrough. The upper end of the bore 4 communicates with an enlarged hollow recess 5, while the lower end of the bore communicates with an enlarged recess 6. A plunger 7 is positioned in the central bore 4 and has a collar 8 keyed thereon in any suitable manner, said collar 8 being positioned in the enlarged recess 5. A plunger head 9 is mounted on the lower end 70 of the plunger 7 and is adapted to be normally received within the enlarged recess 6, by means of a spring 10 which is positioned around the plunger 7, one end of the spring bearing against the end of the enlarged 75 recess 5, while the opposite end of the spring 10 rests in engagement with the collar 8.

The enlarged recess 5 in the top of the handle is closed by means of a cap 11. The plunger 7 extends centrally through the cap 11 and is provided with a head 12, the purpose of which will be better understood as the description follows.

When desiring to use my improved tee forming mold, the mold is pushed downwardly into a sand box, which causes same to form the desired shape, after which the tee mold is deposited on the tee at the desired point and by pressing downwardly on the plunger 7 by bringing the forefinger of the golf player into engagement with the head 12, the enlarged plunger head 9 is forced downwardly into the same, which not only forces the sand from the mold, but also provides a concaved recess as indicated by the letter A in the top of the mold for receiving the golf ball therein.

In view of the foregoing description of my invention, taken in connection with the accompanying drawing, it is thought that any further explanation as to the construction, operation and objects of the invention is unnecessary.

While I have shown and described the preferred form of my invention, I realize that various minor changes may be resorted to, without departing from the spirit and
